UNITED STATES PATENT OFFICE.

JAMES M. KLINE, OF BEAVERTOWN, PENNSYLVANIA.

HYDRAULIC RAM.

SPECIFICATION forming part of Letters Patent No. 758,259, dated April 26, 1904.

Application filed August 17, 1903. Serial No. 169,780. (No model.)

To all whom it may concern:

Be it known that I, JAMES M. KLINE, a citizen of the United States, residing at Beavertown, in the county of Snyder and State of Pennsylvania, have invented a new and useful 5 Hydraulic Ram, of which the following is a specification.

This invention relates to improvements in hydraulic rams.

10 One object of the invention is to provide a ram in which the escape-valve is adjustably weighted, so that a resistance to the closing movement may be altered in accordance with the volume, pressure, or head of the water.

15 A further object of the invention is to provide a ram with an escape-valve opening or port the area of which may be readily adjusted in accordance with the volume of water.

20 A still further object of the invention is to provide a ram in which a volume of impure water, such as the water of a running stream, may be employed to pump pure water, as from a spring, to a house or other point of consumption.

25 A still further object of the invention is to provide a hydraulic ram with an air-chamber that may be readily detached should it become necessary to examine or repair the check-valve, and it may be held in place by means 30 of a small yoke and a single set-screw.

35 A still further object of the invention is to provide a ram in which the entrance and discharge ports are arranged on the same horizontal line, so that the head of the water on entering will serve to assist in discharging the water, and all unnecessary waste of pressure or force will be prevented.

With these and other objects in view, as will more fully hereinafter appear, the invention 40 consists in the novel construction and arrangement of parts hereinafter described, illustrated in the accompanying drawings, and particularly pointed out in the appended claims, it being understood that various changes in 45 the form, proportions, size, and minor details of the structure may be made without departing from the spirit or sacrificing any of the advantages of the invention.

50 In the accompanying drawings, Figure 1 is a longitudinal sectional elevation of a hydrau-

lic ram constructed in accordance with the invention. Fig. 2 is a detail perspective view of the escape-valve, its port, and carrying-lever. Fig. 3 is a similar view of the main check-valve and its cage. Fig. 4 is a detail 55 section of a portion of the air-chamber, showing the pivot-sockets of the air-dome-clamping yoke.

Similar numerals of reference are employed to indicate corresponding parts throughout 60 the several figures of the drawings.

The entrance-chamber 1 of the ram communicates in the usual manner with the air-chamber 2, and between these two chambers is a check-valve 3 to prevent the backflow of 65 water. As the main portion of the ram is formed of rough cast metal, which would prevent the direct application of a valve with expensive finishing, a separate valve-seat 4 is formed of a ring of metal of a shape corresponding to the cross-sectional contour of the inlet and provided with ears or lugs 5, having suitable openings for the passage of securing-bolts. The valve proper is formed of a suitably-shaped piece of leather and is provided 75 with a weight-plate 7, that serves in part to maintain the valve member in proper position, and said plate is confined in place by a suitable bolt 8, extending through the valve and through a small metallic plate 9, arranged at 80 the inner face of the valve and entering the inlet when the valve is closed.

The valve proper may be formed of a piece of leather or other suitable material, and its upper end is somewhat contracted in width 85 and is bent over an upper flange 10 at the upper portion of the stationary base of the ram and is confined in place by a bolt 11, that also extends through the upper end of a plate 12. This plate forms a valve-cage and is held in 90 proper spaced relation to the valve by means of lugs or fingers 13, that rest against the inner wall of the air-chamber, the plate preventing excessive opening movement of the valve.

The water-chamber 1 is provided with a vertically-disposed flange 15, defining an opening 16, which may be of rectangular or other form, and on this flange is seated a cover 17, that may be bolted or otherwise secured to 95 100

the ears or lugs projecting from the flange, and said cover-plate is preferably disposed at an angle to the horizontal in order that the action of the valve, which at times covers 5 openings in the cover, may be made more uniform and regular. The cover 17 is provided with a number of openings 18 and has a revolute regulating-disk 19, provided with similar openings 20.

- 10 The disk is provided with a pair of arcuate slots 21, through which pass bolts 22, the construction permitting rotative movement of the disk to an extent sufficient to secure the regular adjustment of the openings, and by 15 tightening the bolts the disk may be locked in any desired position. This feature is important in that it permits of the adjustment of the device in accordance with the quantity of water, and this prevents the waste of wa- 20 ter in dry season or where a spring or other source of supply is limited.

The escape-valve 22' is formed of a thick disk of rubber carried by a bar 23, that extends through a central opening formed in 25 the disk 19 and the cover 17, and the main body of the bar being hollow and adapted to receive a slidably weight 24. The rear end of the bar extends through a collar 25, formed at the upper end of an arm 26; the lower end 30 of said arm having trunnions 27, adapted to suitable bearings in blocks 28, that are carried by the rearwardly-extended portion of the cover-plate 17 for convenience in manufacture. The hollow bar 23 is locked in the 35 sleeve or collar 25 by means of a pair of set-screws 29, while the weight is held in any position to which it may be adjusted by means of a set-screw 30, passing through a threaded opening in the sleeve or collar and an auxiliary opening in the hollow bar 23. This 40 weight may be adjusted in order that greater or less resistance may be offered to the closing movement of the valve, and thus govern the speed of operation of the ram and the pressure imparted to the water, so that the water 45 may be elevated to a greater or less height.

The air-chamber has a removable dome 31, that is seated on the upper flange of the body portion or box of the air-chamber and is held 50 in place by means of a yoke 32. The lower ends of the yoke are turned inward and are received in suitable openings in opposite sides of the body portion of the air-chamber, while the upper or central portion of the yoke has 55 a threaded opening for the reception of a set-screw 33, which bears against the top of the dome and forces the same firmly against its seat, a suitable packing-ring 34 being introduced between the dome and flange in order 60 to form an air-tight joint.

The eduction-pipe 35 is arranged in a direct horizontal line with a water-supply pipe 36, so that the course of the water entering 65 the water-chamber and from thence passing to the air-chamber may be in a direct line

with the discharge and all of its power utilized, the force of the flow being added to some extent to the reactionary force due to the expansion of air in the dome 31 in order to check the water through the pipe 35. The 70 casing is provided with an opening 37, through which air is admitted to renew the supply in the air-chamber.

In the operation of the ram as thus far described the water entering the chamber 1 75 first escapes past the valve 22 and then in the usual manner closes said valve and forces open the check-valve 3 and passes quickly into the air-chamber, effecting the admission of the air and the subsequent expansion of 80 the air closing the valve 3 and forcing the water to the eduction-pipe 35.

In carrying out the present invention, especially where the water is to be used for drinking purposes and where the supply is 85 limited, it is designed to utilize a body of impure-water for pumping purposes. It often happens that a spring or similar source of pure-water supply is adjacent to a running stream the power of which would be sufficient 90 to force the spring-water to the point of consumption, while the quantity of water in the spring would not be sufficient for the purpose. In such cases the less desirable or impure water may be made to force the spring- 95 water without waste to the point of consumption. This is accomplished by tapping into the air-chamber 1 a feed-pipe 40, communicating with the spring, and the water from the spring flows through this pipe to the water-chamber a constant stream, a check-valve 41 being introduced in the pipe in order to prevent backflow at any time. The purer water will fill the space from a point intermediate of the escape-valve and the pipe 40 100 to the eduction-pipe 35, while the impure water entering through the pipe 36 will not mingle therewith, and the force or head of both bodies of water is utilized in pumping the spring-water through the pipe 35. 110

In the starting of the operation it may be assumed that the two bodies of water entering through the pipes 36 and 40 will both flow in the direction of the escape-valve 22, but owing to the superior volume of impure 115 water a comparative proportion of the spring-water will escape, but the inflow will be sufficient to prevent the purer water from passing beyond the pipe 40. The usual operation will then follow at regular intervals, the escape-valve being closed, and the water in the chamber 1 will be moved in the direction of the air-chamber 2, opening the check-valve 3 against the pressure of air in the chamber 2. It is only 120 the spring-water, however, which enters the air-chamber. On the closing of the check-valve 3 and the regurgitation of the water the small body of spring-water left in the water-chamber will tend to force back the impure water, and both bodies of water will, as before, flow in 130

the direction of the escape-valve. The supply-pipes are so proportioned as to prevent intermingling of any of the impure water with the spring-water, and this can only occur where 5 the volume of spring-water is less than the pumping capacity of the ram. The amount of water utilized may be adjusted by means of the valve 22, and the speed of operation of the ram and the pressure exerted on the water may be readily adjusted by shifting the weight 24 in the hollow bar 23.

Having thus described the invention, what is claimed is—

1. In a hydraulic ram, an escape-valve, a hollow bar carrying said valve, a pivotally-mounted arm having a clamping sleeve or collar for engaging said bar, a slidable weight for which said hollow bar forms a housing and in which it is longitudinally adjustable, 15 and a set-screw carried by the sleeve or collar and extending through an opening in the bar to engage and lock the weight in adjusted position.

2. In a hydraulic ram, a water-chamber having an escape-valve opening, a ported cover-plate for the opening, an escape-valve adapted to seat against the under side of said plate, a pair of spaced bearing-boxes carried by the plate, an arm having trunnions adapted to 20 said bearing-boxes, a sleeve or collar carried by the arm, a hollow bar clamped to said sleeve or collar and connected to the valve, a slidable weight adapted to said hollow bar and a clamping-screw for holding said weight in 25 adjusted position.

3. In a hydraulic ram, a water-chamber having a top wall provided with openings for the escape of water, an upwardly-closing escape-valve adapted to seat against the inner surface of the said wall, a carrying-rod for said escape-valve, a ported regulating-disk held against the outer surface of the wall and adjustable thereon to vary the effective area of the escape-ports, both the regulating-disk and

the upper wall having central openings for 45 the passage of the escape-valve carrying-rod, and means for locking the regulating-disk in adjusted position.

4. In a hydraulic ram, a water-chamber, a detachable ported cover-plate forming the upper wall of the chamber, said plate being provided with a plurality of escape-ports and having an approximately central opening, an escape-valve adapted to seat against the inner face of the plate, a ported regulating-disk for 50 adjusting the effective area of the escape-ports, said regulating-disk being arranged on the upper surface of the plate and being provided with a pair of diametrically-opposed arcuate slots and having a centrally-disposed 55 opening alining with the opening of the cover-plate, guiding and locking bolts extending through the arcuate slots and tapped into the cover-plate, said bolts forming guides for the movement of the disk-valve, and an escape-valve carrying-bar extending loosely through the central openings of the disk-valve and cover-plate.

5. In a hydraulic ram, a box or casing divided into a water-chamber and an air-chamber, a ring arranged around the opening between the two chambers and forming a valve-seat, a flexible valve adapted to the seat and connected at its upper end to the wall of the air-chamber, a weight-plate secured to the 70 lower portion of the valve and serving to hold the same in proper position, and an auxiliary plate having a plurality of studs or fingers and forming a cage for the valve, substantially 75 as specified.

In testimony that I claim the foregoing as my own I have hereto affixed my signature in the presence of two witnesses.

JAMES M. KLINE.
